UNITED STATES PATENT OFFICE

1,924,994

PROCESS AND APPARATUS FOR COATING
PAPERTheodore E. Knapp, Jr., Hamilton, Ohio, assignor
to The Champion Coated Paper Company,
Hamilton, Ohio, a corporation of OhioApplication November 29, 1930
Serial No. 499,078

5 Claims. (Cl. 91—27)

This invention relates to a process of coating paper and to apparatus designed to perform said process.

The term "coated paper" is here used in the sense in which it is commonly employed in the paper industry, that is to say, paper which has been coated with a fluid suspension of mineral pigment, such as clay, satin white and the like, in an aqueous solution of an adhesive such as 10 casein, starch and the like, and the terms "coating", "aqueous coating", "coating mixture", etc., as used herein, are to be interpreted in accordance with this definition.

In United States Patent No. 1,774,398 there 15 is disclosed a process and apparatus for coating paper in which the brushes commonly used to smooth and distribute the coating on the paper web or sheet are replaced by metallic, e. g. steel surfaced rolls, rotating reversely to the direction of movement of the paper. One objection to this type of coater is that the coated paper so made is marred by ridges in the coating extending lengthwise of the travel of the sheet. These ridges, under proper operation of the coater, may 20 not be very heavy, but they are characteristic of coated paper so made, and naturally this impairs its use for certain purposes such as fine half-tone printing where an exceedingly smooth surface is required.

25 The present invention contemplates a coater in which the difficulties inherent in the use of reversely turning metallic, e. g. steel smoothing and distributing rolls, are overcome.

The invention will be described by reference 30 to the accompanying drawing.

Fig. 1 is a diagrammatic representation of the essential parts of the coater;

Fig. 2 is a diagrammatic view of one of the smoothing rolls.

40 While the drawing illustrates and the following description refers only to cylindrical rolls, it will be understood that other devices such as a traveling belt might be substituted therefor.

Referring to the drawing, 2 is the web of paper 45 to be coated, supplied from the roll thereof of 1. 3 and 4 are guide rolls, and 5 is a supporting roll around which the paper travels. 6 is a pan of coating mixture into which the roll 7 dips. 8 is a large rotating brush which picks up coating 50 from the roll 7 and deposits it on the paper as it passes around the roll 5. The weight of coating so applied to the paper may be controlled in the well-known manner, as by regulation of the relative speeds of rotation of rolls 7 and 8 and 55 the travel of the paper web. 9 is an apron travel-

ing on rolls 11 and 12, which serves to draw the paper through the machine. 10, 10, 10, are smoothing rolls driven in the reverse direction to the movement of the paper, preferably at a surface speed greater than and desirably two or more times that of the paper. 13, 14, 15 and 16 are supporting rolls. After contact with these smoothing rolls the paper is carried by the belt 9 to a drying system, for example a festoon line, not shown. Each of the smoothing rolls 10 consists of a wood or metal core 17 carried on a shaft 18 and provided with a surface or covering 19 of soft, fibrous material which, in contradistinction to the steel or steel surfaced rolls above referred to, are yielding and pervious or absorptive to the aqueous coatings used. I prefer to use a covering of plush which provides a relatively dense, uniform, soft and pervious surface. In place of plush a variety of materials of a fibrous nature, such as various grades of felt, 75 may be used. These rolls may be mounted in adjustable brackets to allow their being moved nearer to or further from the coating applying means as may be desirable in applying different grades or consistencies of aqueous coating mixture. 80

Like the reversely turning steel rolls described in the above-mentioned patent, my smoothing rolls exert a smoothing action on the coating on the sheet by picking up a portion of the coating 85 and redepositing it on the sheet. But apparently due to the character of the surface of my rolls there is little or no tendency for the coating to draw up into ridges such as occurs when an impervious or steel roll is used. This tendency to 90 draw up into ridges on a rotating smooth impervious roll is a very general phenomenon with liquids, but in the case of such materials as varnish, liquid wax and the like, the ridges also tend to flow out rapidly so that a fairly uniform deposit 95 of coating of such liquids may result. However, with the coatings used in making coated paper, which consist of a relatively high percentage of insoluble mineral pigments suspended in an aqueous colloidal solution of casein, starch, glue or 100 the like, and which to a degree are gelatinous in character, the ridges form on but do not flow out on an impervious roll, and consequently these ridges are transferred to the paper. In the case of rolls having a fibrous surface these ridges are 105 much less pronounced.

The invention will, therefore, be seen to reside in (1) a method of coating paper comprising applying an aqueous coating to a traveling web of paper in controlled weight and spreading said 110

coating by picking up the coating and redepositing it upon the traveling web of paper by one or more cylindrical bodies presenting a fibrous surface and rotating oppositely to the direction of travel of the paper and preferably at a peripheral speed greater than that of the paper, and (2) in apparatus for making coated paper comprising means for applying aqueous coating mixture to a web of paper, means for regulating the weight of coating applied, means for advancing the web of paper, and means for smoothing the coating on the web, said last means comprising one or more rolls presenting a flush surface, and means for rotating said rolls oppositely to the direction of travel of the paper.

I claim:

20 1. Process of coating paper which comprises picking up aqueous coating material from a traveling web of paper and redepositing it thereon by means of one or more yielding absorptive surfaces moving oppositely to the direction of travel of the paper.

25 2. Process of coating paper comprising applying an aqueous coating to a traveling web of paper in controlled weight and spreading said coating by picking up coating material from and redepositing it upon the traveling web of paper by means of one or more yielding, absorptive surfaces moving oppositely to the direction of travel of the paper at a speed greater than that of the paper.

35

3. Apparatus for making coated paper comprising means for applying aqueous coating mixture to a web of paper, means for regulating the weight of coating applied, means for advancing the web of paper, means for smoothing the coating on the web, said last means comprising one or more rolls presenting a flush surface, and means for rotating said rolls oppositely to the direction of travel of the paper.

80

4. Apparatus for coating paper comprising means for applying aqueous coating mixture to a web of paper, means for regulating the weight of the coating applied, means for advancing the web of paper, means including a roll having a yielding, absorptive surface for smoothing the coating on the web and means for rotating said roll oppositely to the direction of travel of said web at a peripheral speed greater than the speed of the web.

85

5. Apparatus for making coated paper, comprising means for applying aqueous coating mixture to a web of paper, means for advancing the web of paper, means for smoothing the coating on the web, said last means including a roll having a fibrous, yielding surface constituting means for carrying a layer of coating material without substantial transverse movement of said layer on said roll into longitudinal ridges and means for rotating said roll oppositely to the direction of travel of the web and at a peripheral speed greater than the speed of the paper.

CERTIFICATE OF CORRECTION.

Patent No. 1,924,994.

August 29, 1933.

THEODORE K. KNAPP, JR.

It is hereby certified that error appears in the printed specification of the above numbered patent requiring correction as follows: Page 2, line 82, claim 3, for "flush" read "plush"; and that the said Letters Patent should be read with this correction therein that the same may conform to the record of the case in the Patent Office.

Signed and sealed this 24th day of October, A. D. 1933.
